UNITED STATES PATENT OFFICE.

ARTHUR R. BECK, OF AMES, IOWA, ASSIGNOR OF ONE-HALF TO RILEY J. BECK, OF SIOUX CITY, IOWA.

OIL CAN.

Application filed February 8, 1922. Serial No. 534,940.

REISSUED

To all whom it may concern:

Be it known that I, ARTHUR R. BECK, a citizen of the United States, and a resident of Ames, in the county of Story and State of Iowa, have invented a certain new and useful Oil Can, of which the following is a specification.

My invention relates to that class of oil cans in which a force pump is employed to project the oil from the spout.

The objects of my invention are to provide an oil can of this class of simple, durable and inexpensive construction.

More specifically it is my object to provide an oil can of this class in which the pump, the screw cap, the oil can, the feed pipe and the handle are all firmly united and connected together so they will always maintain their proper relationship to each other, and also so that a new can or a new spout may be readily, quickly and easily applied.

A further object is to provide an improved valve mechanism of simple, durable and inexpensive construction, and so arranged that the two valves are readily and easily accessible and removable and may be interchanged.

My invention consists in the construction, arrangement and combination of the various parts of the device, whereby the objects contemplated are attained, as hereinafter more fully set forth, pointed out in my claim, and illustrated in the accompanying drawings, in which:

Figure 1 shows a side elevation of an oil can embodying my invention.

Figure 2 shows a top or plan view of the same.

Figure 3 shows an enlarged, detail, sectional view through the pump and feed pipe and screw cap for the can end part of the handle and discharge spout.

Figure 4 shows an enlarged, detail, perspective view of one of the valves.

Referring to the accompanying drawings, I have used the reference numeral 10 to indicate the screw cap for the oil can. Permanently fitted to the screw cap is a feed pipe 11, and fitted to both the screw cap and the feed pipe is a pump cylinder 12.

At the upper end of the feed pipe 11 there is formed a valve chamber, the upper edge of which is screw threaded to form a socket

13 for the reception of the lower end of the screw threaded discharge spout 14. When the discharge spout is screwed into position, it engages a valve body 15 and serves to hold it in position. This valve body comprises a circular, flat metal member having an opening through its center, and a flat metal valve 16 is mounted on its top above the opening.

For holding the valve in place, and at the same time permitting it to function as a valve, I have provided a rod 17 with its ends fixed to the valve body 15, and its central portion extending over the top of the valve. At one end of the valve there is a round opening into which the rod 17 is received. At the other end, there is a slot 18 into which the opposite end of the rod 17 is received.

This rod 17 performs the additional function of serving as a handle by which the valve body may be grasped to remove it from the valve seat, when the spout has been removed. It also serves to limit the upward movement of the valve.

At the lower end of the feed pipe 11 I have provided a screw cap 19 into which the lower valve is inserted. This lower valve is of exactly the same size, shape and construction as the upper valve before described.

Mounted in the pump cylinder 12 is a piston 20 which projects out through an opening in a screw cap 21 on the outer end of the pump cylinder, and a handle 22 is secured to the piston and provided with a rounded loop 23 at its outer end.

The handle 22 is preferably formed of a single piece of wire or rod having a loop 24 which surrounds the body portion of the can, and a handle 25 and another loop 26 at its upper end which extends around the screw cap 10 and on opposite sides of the pump cylinder, and which is secured by soldering or otherwise to the screw cap 10.

The can is filled by simply removing its screw cap 10 in the ordinary way, and when this is done, the pump and discharge spout may become separated from the can. This unscrewing of the cap from the can is done very readily and easily because the operator may grasp the handle with one hand and the can with the other, and use the can as a lever for removing the screw cap. The proper relationship is always maintained be-

tween the handle and the pump rod so that the operator may insert his thumb in the loop 23 of the pump rod, and grasp the handle in the palm of his hand, and then 5 readily and conveniently manipulate the oil can and place it in any desired position, and at the same time he can operate his thumb readily, easily and conveniently to apply pressure to the oil, and with this arrangement 10 no spring in the pump is necessary.

Furthermore, when the pump is not being used, the pump rod and its loop 23 may be retained in position close to the pump cylinder, whereas with the kind of oil cans in 15 which a spring is employed in the pump, the pump rod always projects outwardly from the pump cylinder.

In the event that any injuries occur either 20 to the oil can or the discharge spout, either one or the other may be easily and quickly removed and a new one substituted, and any ordinary oil can or discharge spout may be employed because none of the pump mechanism or valves, or handle is connected permanently 25 to either the oil can or the discharge spout.

Furthermore, in the event that either valves should for any reason become inoperative, the operator can readily and easily 30 remove it, and either fix it or substitute a new one.

If it is desired to remove the upper valve 35 the operator simply unscrews the upper spout and grasps the rod 17 and lifts the valve and valve body out of its seat; or if it is desired to remove the lower valve, he simply unscrews the cap 19 and the lower

valve can be removed from the can by grasping the rod 17.

I have also found in practice that the specific construction of the valve is beneficial and advantageous, because by having a round opening at one end and a slot at the other through which the rod 17 is extended, the valve will open freely with a hinge-like movement centered at the side in which the round opening is located, and it will not slide up the rods 19 away from the valve body and stick in this position, which sometimes occurs when no slot is provided for one end of the valve.

I claim as my invention:

An improved oil can comprising an oil can body having a screw threaded opening at its top, a screw cap for the oil can, a feed pipe permanently fixed to the screw cap and having a valve at its lower end, its upper end above the screw cap being formed with a valve seat, and a screw threaded extension above the valve seat, a valve mounted in said valve seat, a discharge spout screwed into the said screw threaded extension and engaging the valve body, a pump cylinder permanently fixed to the screw cap and communicating with the upper end of the feed pipe, a piston therein, a piston rod connected with the piston and provided with a loop, and a handle for the oil can loosely encircling the body portion of the oil can and permanently fixed to the screw cap, for the purpose as stated.

Des Moines, Iowa, January 25, 1922.

ARTHUR R. BECK
